UNITED STATES PATENT OFFICE.

JULIUS AISENSTEIN, OF NEW YORK, N. Y.

DESIGN FOR A BUTTON, BADGE, OR SIMILAR ARTICLE.

55,229.

Specification for Design.

Patented May 25, 1920.

Application filed January 10, 1919. Serial No. 270,593. Term of patent 3½ years.

To all whom it may concern:

Be it known that I, JULIUS AISENSTEIN, a citizen of Russia, and a resident of the borough of Manhattan, city, county, and State of New York, have invented a new, original, and ornamental Design for a Button, Badge, or Similar Article, of which the following is a specification, reference being had to the accompanying drawing, forming part thereof.

The figure is a face view of a button, showing my new design.

I claim:

The ornamental design for a button, badge, or similar article, as shown.

In testimony whereof I have signed this specification.

JULIUS AISENSTEIN.
